S. PEACOCK,
APPARATUS FOR ANNEALING THIN STEEL SHEETS.
APPLICATION FILED NOV. 9, 1920.

1,427,319.

Patented Aug. 29, 1922.

UNITED STATES PATENT OFFICE.

SAMUEL PEACOCK, OF WHEELING WEST VIRGINIA, ASSIGNOR, BY MESNE ASSIGNMENTS, TO WHEELING STEEL & IRON COMPANY, OF WHEELING, WEST VIRGINIA, A CORPORATION OF WEST VIRGINIA.

APPARATUS FOR ANNEALING THIN STEEL SHEETS.

1,427,319.

Specification of Letters Patent. Patented Aug. 29, 1922.

Application filed November 9, 1920. Serial No. 422,814.

To all whom it may concern:

Be it known that I, SAMUEL PEACOCK, a citizen of the United States, residing at Wheeling, in the county of Ohio, and State of West Virginia, have invented certain new and useful Improvements in Apparatus for Annealing Thin Steel Sheets; and I do hereby declare the following to be a full, clear, and exact description of the invention, 10 such as will enable others skilled in the art to which it appertains to make and use the same.

This invention relates to an apparatus for annealing thin sheets of steel preparatory to 15 coating them with tin, and has for its object to provide a means by which said annealing may be accomplished out of contact with the air, and in a manner more expeditious and less costly than has been heretofore proposed.

With these and other objects in view the invention consists in the novel details of construction, and combinations of parts constituting the apparatus, all as will be more 25 fully hereinafter disclosed and particularly pointed out in the claims.

Referring to the accompanying drawings forming a part of this specification, in which like numerals designate like parts in all the 30 views:

Figure 1 is a sectional view of an apparatus made in accordance with this invention;

Figure 2 is a sectional view of the base portion of the apparatus detached from the 35 cover portion thereof; and

Figure 3 is a plan view partially broken away, of the parts shown in Figure 2.

In order that the precise invention may be the more clearly understood, it is said:

40 As is well known in the coating of thin steel sheets with tin, it is necessary to thoroughly descale the sheets before subjecting them to the tin bath, and that this involves an annealing step to soften the plates, then a pickling bath to deprive said sheets of their oxide coatings, then a rolling operation to smooth the surfaces of the sheets; then a second annealing process to take out the strains produced by rolling and then a second pickling operation to get rid of the oxides formed during the second annealing operation.

From the foregoing it will be seen that if either of the annealing steps could be car-

ried out in an atmosphere devoid of oxygen 55 such as a substantial vacuum, or in an atmosphere of a reducing gas, the oxides would not be formed on the plates, and that therefore, the process of coating with tin could be very much lessened in cost. Accordingly, the object of this invention, more 60 specifically stated, is to provide an apparatus by which thin steel sheets to be converted into the tin plate of commerce, may be annealed without suffering the objectionable 65 oxidation heretofore experienced.

Referring to the accompanying drawings forming a part of this specification,

1 indicates any suitable supporting base preferably of iron; 2 a foundation of refractory non-conducting material such as fire brick resting upon the base 1; 3 a plate like foundation preferably of metal resting upon the brick 2; and 4 non-conducting sheets such as asbestos resting upon the 75 plate 3. Located upon the asbestos sheets 4 are the piles 5, 6 and 7 of thin steel sheets to be annealed. The said foundation plate 1 is provided with suitable supports or legs 8, as shown, and also with any suitable means 80 such as 9 by which it can be readily, together with its burden, moved from place to place by means of a crane or other lifting apparatus. 10, 11, 12, and 13 represent a plurality of metal hoods or covers adapted to completely enclose the packs of steel sheets 5, 6, 7; and 14, 15, and 16 represent air spaces between said members 10, 11, 12 and 13 in order to heat insulate the interior from the exterior.

Said covers 10, 11, 12, and 13 are conveniently spaced apart by the heat insulating members 17, 18, and 19, which are preferably staggered as shown, and said enclosing members are further provided with the flange or 85 feet like members 20, 21, 22, and 23, fitting each other as illustrated and the lowest one, 20, of which fits against the asbestos pad 24, as will be readily understood from the drawings.

25 and 26 represent clamp members pivoted as at 27 and provided with the screw means 28 adapted to clamp the feet like members 20, 21, 22, and 23 tightly against each other and against the pad 24, so as to 105 make the enclosure air-tight.

Supported from the enclosing members as by the rod 30 is the wire supporting means

31 carrying a plurality of electrical resistance heating members 32, 33, 34, and 35 adapted to fit the spaces between the packs of plates 5, 6, and 7 and between said packs 5 and the inner wall of the enclosing member 10, as illustrated. Said member 31 as well as said enclosing members 10, 11, 12, and 13 are further supported and bound together by the central rod 36 provided with the 10 ring like member 37 adapted to be engaged by a lifting crane so that the cover members 10, 11, 12, and 13, the heating members 32, 33, 34, and 35, and all other parts that are rigid with said cover members may be 15 bodily lifted off the base member 1 and from over the packs of plates 5, 6, and 7, to expose said plates for a ready removal after the annealing process has been completed.

40 represents a pipe which enters the enclosure and it may serve as a means for exhausting said enclosure of air or of introducing into said enclosure a reducing gas such as CO, or an inert gas such as nitrogen. 41 represents a pressure gauge to indicate 25 the degree of vacuum, and a thermometer, not shown, is also conveniently provided in order to indicate the temperature existing at any particular time on the interior of said enclosure.

30 The operation of this invention will be clear from the foregoing, but may be briefly summarized as follows: The packs of sheets 5, 6, and 7 are stacked upon the metal base plate 3 as indicated, the asbestos sheets 4 being interposed as illustrated, to prevent the hot sheets from sticking to the plate 3, whereupon for convenience of treatment and to save space, in the rolling mills, the base plate 1 together with said packs 5, 6 and 7 35 is picked up by a crane not shown, which lowers the said base plate 1 to the position selected, whereupon the same crane, or another, picks up the cover members 10, 11, and 12 together with the heating members 40 45 32, 33, 34, and 35, and lowers the same down over the packs 5, 6, and 7 into the positions indicated in Figure 1, whereupon the clamping members 25 are adjusted, all around the base plate 1, and an air tight 50 joint is made therewith, as will be readily understood.

Then a vacuum is created on the interior of the cover members by means of suction through the pipe 40, or producer gas or 55 nitrogen gas is let into said space, whereupon current is turned on through the leads 45 and 46, and the resistors 32, 33, 34, and 35 are heated up. Heat is maintained at the proper well known temperature and for 60 the well known time necessary to properly anneal said plates, whereupon the current

is turned off and it will be found that the asbestos plates will have prevented the lower sheets of the packs 5, 6 and 7 from sticking to the metal plate 3, and it will be found 65 that the said metal plate 3 will have prevented the softening or the deterioration and depression of the fire brick 2 under the relatively high temperatures employed.

The air spaces 14, 15, and 16 will prevent 70 the escape of heat to a material extent and therefore the process will be carried out with a minimum expenditure of heat energy.

In order that the lower sheets of the packs 5, 6 and 7 may be properly heated up the 75 resistor members 50 are conveniently located within the metal plate 3 and serve to transmit heat through the relatively thin asbestos sheets 4 to said lower sheets of the packs 5, 6, and 7.

It is obvious that those skilled in the art may vary the details of construction, as well as the arrangement of parts without departing from the spirit of the invention, and therefore I do not wish to be limited to the 85 above disclosure except as may be required by the claims.

What is claimed is:

1. In an apparatus for annealing thin sheets of steel, the combination of a metal 90 base plate; a mass of refractory non-heat conducting material carried by said base plate; means for supporting said steel sheets in packs on said mass; a heat insulating cover comprising a plurality of metal members spaced apart and provided with air spaces between them; enclosing said mass and packs of sheets; means to form an air-tight joint between said base plate and said cover; means to exhaust the air from around 95 said packs; and electric heating means for heating said packs to an annealing temperature, substantially as described.

2. In an apparatus for annealing thin sheets of steel, the combination of a metal base plate; a mass of refractory non heat conducting material carried by said base plate; means comprising a metal slab having spaces to receive electric heating means for supporting said steel sheets in packs on 100 said mass; a heat insulating cover composed of a plurality of members separated by air spaces enclosing said mass and packs of sheets; means to form an air tight joint between said base plate and said cover; means to exhaust the air from around 110 said packs; and means comprising electric circuit connections and electric resistors for heating said packs to an annealing temperature, substantially as described.

In testimony whereof I affix my signature.
SAMUEL PEACOCK.
